(57)

CLAIM

The ornamental design for a signal device as shown and described.

DESCRIPTION

FIG. 1 is a perspective view of the new design;

FIG. 2 is a front view of FIG. 1;

FIG. 3 is a rear view of FIG. 1 the left side being the same image thereof;

FIG. 4 is a right side view of FIG. 1;

FIG. 5 is a top view of FIG. 1; and,

FIG. 6 is a bottom view of FIG. 1.

The broken lines depict environment and form no part of the claimed design.

1 Claim, 5 Drawing Sheets
